UNITED STATES PATENT OFFICE.

HENRY M. CAMPBELL, OF BAY CITY, MICHIGAN.

PACKING DEEP-WELL PUMPS.

SPECIFICATION forming part of Letters Patent No. 318,447, dated May 26, 1885.

Application filed June 20, 1884. (No model.)

To all whom it may concern:

Be it known that I, HENRY M. CAMPBELL, a citizen of the United States, residing at Bay City, in the county of Bay and State of Michigan, have invented a new and useful Improvement 5 in Packing Deep-Well Pumps, of which the following is a specification.

Heretofore when the packing in deep-well pumps required tightening it has been necessary to take all the tubing, well-poles, and 10 pump out of the well, at considerable expense, trouble, and loss of time, in order to get at the pump to tighten the packing therein.

15 The object of my invention is to provide a means by which the packing in these pumps can be tightened in a few minutes' time at very slight expense and without removing the pump from the well. I attain this object by 20 the mechanical device set forth in the annexed drawings, in which—

Figure 1 is a side view of a deep-well pump-barrel, stuffing-box, and plunger, with one side left off to show the flexible packing and 25 my device for tightening the same. Fig. 2 shows a section of the plunger to the pump with my improvement of collar and lugs forged thereon. Fig. 3 is a top view of my improved follower or gland. Fig. 4 shows a vertical section of the said follower.

Like letters refer to like parts in the several views.

In Fig. 1, F represents a pump-plunger in pump-barrel E, passing through stuffing-box 30 a and flexible packing G, also through follower C. This plunger F is made of wrought-iron, and forged with the collar B and lugs c c all in one piece, with orifice b through top, where the water escapes into tubing D, and 35 with thread e run on its top, for connection with poles leading to the top of well.

C is a brass gland or follower, fitting closely around plunger F in stuffing-box a. It has slots d d cut in opposite sides of its top, and is held firmly in position by and runs in a 45 thread cut on the inside of stuffing-box a. The plunger F ordinarily works with the collar B above the stuffing-box a; but when it becomes necessary to tighten the packing in stuffing-box a the plunger F (connected with 50 poles leading to the top of well) can be lowered sufficient to let lugs c c drop into slots d d, when by means of a wrench or clamps in the hands of an operator at top of well the follower C can be screwed down on and tighten 55 the packing in box a, after which the plunger F may be raised to its former position and the pumping proceed as before.

Having fully described my invention, what I claim, and desire to secure by Letters Patent, is—

1. In a deep-well pump, the projecting collar B, provided with lugs c c in connection with plunger F, having orifice b and thread e, for the purposes specified. 65

2. In a deep-well pump, the combination, with stuffing-box a and flexible packing G, of the follower C, provided with slots d d, for the purpose set forth.

3. In a deep-well pump, the combination, 70 with collar B and lugs c c, of the follower C and slots d d, all substantially as shown, and for the purpose specified.

In testimony whereof I have affixed my signature in presence of two witnesses.

HENRY M. CAMPBELL.

Witnesses:

W. J. McCORMICK,
LANE LYLE.
